DESIGN FOR A DISPLAY STAND OR SIMILAR ARTICLE

Eugene Schwartz, Philadelphia, Pa., assignor to
The Ketterlinus Lithographic Manufacturing
Company, Philadelphia, Pa., a corporation of Pennsylvania

Application October 31, 1936, Serial No. 65,623

Term of patent 7 years

To all whom it may concern:

Be it known that I, Eugene Schwartz, a citizen of the United States of America, residing at Philadelphia, in the county of Philadelphia and State of Pennsylvania, have invented a new, original, and ornamental Design for a Display Stand or Similar Article, of which the following is a specification, reference being had to the accompanying drawing, forming part thereof, in which:

Fig. 1 is a front elevational view of the display stand, showing my design;

Fig. 2 is a side elevational view;
Fig. 3 is a top plan view; and
Fig. 4 is a side elevational view of the display stand in collapsed position.

I claim:

The ornamental design for a display stand or similar article as shown and described.

EUGENE SCHWARTZ.
